No. 764,343.

UNITED STATES PATENT OFFICE.

LEANDER P. BOWEN, OF AUBURN, NEW YORK.

SHOE-RACK.

SPECIFICATION forming part of Letters Patent No. 764,343, dated July 5, 1904.

Application filed April 22, 1904. Serial No. 204,412. (No model.)

To all whom it may concern:

Be it known that I, LEANDER P. BOWEN, of Auburn, in the county of Cayuga, in the State of New York, have invented new and useful 5 Improvements in Shoe-Racks, of which the following, taken in connection with the accompanying drawings, is a full, clear, and exact description.

This invention relates to improvements in 10 shoe-racks, having more particular reference to their detail construction, upon which shoes are placed and held during the process of manufacture and drying.

My object is to improve upon the general 15 construction of the uprights or standards at the end, so as to provide for and guard against the checking or splitting thereof; and to that end my invention consists in the several new and novel features of construction hereinafter 20 described, and specifically set forth in the claims hereunto annexed, reference being had to the accompanying drawings, in which—

Figure 1 is a symmetrical elevation of the 25 rack complete. Fig. 2 is an end view thereof. Fig. 3 is a top plan of Fig. 2.

In the drawings, *a* is a frame having cross-bars *a'* and mounted upon casters in the usual way. Upon the cross-bars *a'* are mounted the 30 uprights or standards, made in two parts *b* and *b'* and recessed, as shown at *c*, to receive the bars *d*. The recesses *c*, however, are not deep enough to admit the full width of the bar *d*, so that when they are mounted, as shown Fig. 2, the bars will extend beyond the 35 face of the uprights *b* and *b'*, so as to hold them a short distance apart.

e represents bolts, passing transversely through the uprights *b* and *b'* and through the bar *d* and serves to not only hold bars *d* in place, but also to clamp the uprights together. The bars *d* are provided with the usual laterally-extending pins or pegs by which the shoes are supported.

It will be observed that when the material from which the uprights are constructed is 45 shrunk, as it necessarily will be after having stood in a dry place for a long time, the bars may be tightened and brought into shape again and alinement by tightening the nuts upon the bolts.

Having thus described my invention, what I claim, and desire to secure by Letters Patent, is—

1. A shoe-rack comprising a frame, having uprights, recesses in adjacent faces of said 55 uprights, bars having laterally-extending pegs adapted to rest in said recesses, means for securing the uprights together through said bars.

2. A shoe-rack comprising a frame, having 60 uprights constructed in two parts recessed in their adjacent faces, bars of a greater depth than said recesses mounted therein and means for securing said uprights together as set forth.

In witness whereof I have hereunto set my hand this 16th day of April, 1904.

LEANDER P. BOWEN.
